UNITED STATES PATENT OFFICE

JESSE A. B. SMITH, OF STAMFORD, CONNECTICUT, ASSIGNOR TO UNDERWOOD ELLIOTT FISHER COMPANY, OF NEW YORK, N. Y., A CORPORATION OF DELAWARE.

TYPEWRITING MACHINE.

Application filed December 12, 1925. Serial No. 74,958.

This invention relates to a device for facilitating the manipulation of work-sheets in typewriting machines of the well-known Underwood fan-fold type.

5 In said fan-fold machines, a multiple ply web is usually drawn up from a supply at the rear of the machine, the plies being interleaved with carbons, forming a pack which is inserted around the platen to be 10 typed upon; the platen being elevated at intervals to reposition the carbons to a fresh portion of the web.

Sometimes it is desired to insert a cut form in registration with the first form of 15 the web, because, in some cases, it is necessary to use one form to send to a customer, in which case a good grade of paper is used, and the balance of the forms are used for interdepartmental work, which, of course, 20 does not require as good a grade of paper.

According to the method of using this kind of a machine, the web is first fed up to a positioning gage, and then the platen is elevated, while the leading edge of the web 25 is held with one hand against the gage, the cut form being inserted between the platen and the feed-rolls, in a preliminary registering position with the first form of the web. The platen is then lowered to its normal 30 position and is rotated rearwardly, so as to bring the leading edge of the cut form and of the web together, the two being reinserted under a knife in front of the platen, and both being positioned for the first line 35 of typing. It will be understood that in order to manifold the first ply of the web, a carbon must interleave said ply and the cut form, and, to this end, it is proposed to use an extra carbon underlying the first 40 ply of the web.

After completely typing the first form, the platen is rotated to feed the web against a cutting-off gage, and by so doing, the cut form is ejected, the platen being again elevated to strip the carbons previously to tearing off the printed form of the web.

One of the features of this invention relates to a gage for positioning the cut form. Said gage has a turned-up edge for positioning the leading edge of the cut form, and a side gage for positioning said form laterally. Means are also provided for holding the cut form when the platen is lowered to its normal position. Said means may be

in the form of a clip forming an integral 55 part of the upturned edge, which positions the cut form in a line-space direction.

Another feature of this invention relates to a gage for positioning the web in registering position with the cut form. Said 60 gage is adjustably mounted on the front table and is provided with an upturned side edge for laterally positioning the web and to prevent its accidental displacement during the platen elevating operation. 65

Other features and advantages will hereinafter appear.

In the accompanying drawings,

Figure 1 is a cross-sectional view, in elevation, through the center of an Underwood 70 fan-fold typewriting machine, and shows the invention applied thereto.

Figure 2 is an operating side view, showing the platen in its elevated position, and shows also the cut form being inserted between the platen and the feed-rolls. 75

Figure 3 is an operating view, showing the platen in its normal position, the knife being lowered to engage the leading edges of the web and the cut form. 80

Figure 4 is an operating view, showing the manner in which the cut form is ejected from the machine previous to tearing off the web to a form-length. 85

Figure 5 is a plan view, showing all the parts in the position corresponding to that shown in Figure 1.

Figure 6 is a perspective view of the adjustable gage mounted on the front table, for positioning the web in line-space direction. 90

Figure 7 is a perspective view of the adjustable gage, which is mounted on the carriage for positioning the cut form, and shows a clip for holding the form in inserted position. 95

Although this invention is illustrated as applied to an Underwood fan-fold typewriting machine of the type such as disclosed in the patent to Wernery & Smith, No. 1,132,055, it will be understood that the invention could also be used to advantage in combination with any typewriting machine having a platen-elevating mechanism. 100

In said fan-fold machine a platen 10 is 105 revolvably mounted on platen-frame 11, which is pivotally mounted on a shaft 12. The platen is operatively connected to finger-

pieces 13 by means of gears 14 and 15, which mesh with pinions 16, said gears 14 being fast to a platen-axle 17.

According to the method of handling the work in this invention, a fan-fold web 18 is drawn up from a supply at the rear of the machine, and is interleaved with carbons 19 fast to a carbon-carrier 20. Besides the interleaved carbons 19, there is provided an extra carbon 21 which underlies the web. The assembled pack, which comprises the web and the carbons, is passed over a table 22, and is inserted under the platen between co-operating feed-rolls 23. The platen is then rotated with one hand to feed the pack around to a positioning gage 24, while its leading edge is held down against a table 25 with the other hand 26.

The platen is held in its normal position, as shown in Figure 1, by means of a latch 27, which engages a pin 28 on the frame 11, and in order that the platen may be partly elevated, as shown in Figure 2, the latch 27 is swung backwardly away from the pin 28. The platen is held in this position with one hand while a cut form 29 is inserted between the feed-rolls and the platen and is laterally positioned against a side gage 30. The form is then pulled over against a leading-edge gage 31, and is held in place by means of a finger 32, while the platen is again lowered to its normal position.

The leading edge gage 31 is adjustably mounted on the carriage, and, by means of this adjustment, it is possible to so position the cut form with relation to the leading edge of the web, that when the platen is rotated rearwardly, to draw the cut form and the web together, the leading edges of both are matched. The platen is again rotated forwardly and the leading edge of the web is inserted under a knife 33, which serves as a means of cutting off the web and also for guiding the leading edge thereof when the same is swung down to the position shown in Figure 3, and the cut form is positioned for the first line of typing.

After completely typing the first form by means of type-bars 34, the platen is rotated forwardly to feed the web against a cutting-off gage 35 and to eject the cut form, as shown in Figure 4. The platen is then lifted, and the leading edge of the web is held against the gage 35 when the carbon-carrier 20 is moved rearwardly by means of a handle 36, the platen being again lowered to its normal position, so as to hold the web while the first form is being torn off against the knife 33.

In order to prevent accidental shifting of the web when the platen is partially elevated to insert a cut form thereunder, the gage 24 is provided with a side gage 37 forming an integral part thereof, the gage 24 being secured to the table 25 by means of screws

38, which are passed through slots 39, thus providing an adjustable gage for positioning the web in line-space direction.

The gage 31 is adjustably mounted upon an adapter 40, which is secured to carriage 41 by means of screws 42 and serves as a means for positioning the gage in a plane tangential to the platen. The gage 31 forms an integral part of a plate 43 against which the finger 32 bears to hold the cut form 75 thereon. Said plate 43 is provided with slots 44 to permit the line-spacing adjustment of the cut form, and is secured to the adapter by means of screws 45.

In order to prevent the back-sliding of the web during the platen elevating operation, and in order to provide a loop under the platen, as shown in Figure 2, thus diminishing the effort required to hold the web against the gage 24, there may be provided springs 45^a secured to the carbon-carrier by means of screws 46, said springs being designed to bear upon rails 47 which serve as a guide for the carbon-carrier. Said springs provide a slight drag on the carbon-carrier, thereby preventing its accidental back movement due to the weight of the web.

In the Underwood machine the knife 33 is fast to end plates 48 pivotally mounted on the platen-axle 17 and may be swung, by means of a finger-piece 49, from its normal position shown in Figure 1 to the position shown in Figure 3, in which the finger-piece 49 is shown under the pressure of a finger 50.

Variations may be resorted to within the scope of the invention, and portions of the improvements may be used without others.

Having thus described my invention, I claim:

1. The combination in a typewriting machine having a carriage, a platen, feed-rolls therefor, means for elevating the platen away from the feed-rolls, and a course at the introductory side of the platen for conducting a work-web to the platen, of a two-part sheet-collating means including an up-standing collating table at the delivery side of the platen in rear of the work-web and having a gage for positioning the leading end of the web, and also including another collating table in front of said work-web for temporarily positioning a downwardly-inserted loose sheet in front of the work-web and in registration therewith, said front collating table having a collating gage adjustably mounted on the carriage relatively to the printing line and spaced forwardly from the platen, and means for detaining the loose sheet in its temporary position at said spaced gage, to permit both the manipulation of said work-web by both hands and the lowering of the platen to its normal position without displacing the loose sheet.

2. In a typewriting machine, in combina-

100

105

- tion, means at the introductory side of the platen for conducting and laterally positioning a web having a superposed carbon, feed-rolls on the platen for feeding said web therearound, sheet-collating means including a gage at the delivery side of the platen for positioning the leading end of the web, means for elevating the platen away from the feed-rolls to permit the downward insertion of a separate loose sheet between the platen and the feed-rolls, and means cooperating with the gage to collate the leading ends of the web and loose sheet in registration and including a frame having an upturned edge for locating the loose sheet by its leading edge, an upturned edge for laterally positioning said loose sheet, and a finger for holding the loose sheet against said edges. 65
- 20 3. In a typewriting machine, in combination, sheet-collating means including means at the introductory side of the platen for conducting and laterally positioning a web having a superposed carbon, feed-rolls running on the platen for feeding said web therearound, a collating gage at the delivery side of the platen for positioning the web in line-space direction, means for elevating the platen away from the feed-rolls to permit the positioning of a downwardly-inserted separate loose sheet in preliminary registration between the platen and the feed-rolls, side and front collating gages spaced forwardly from the platen for positioning the loose sheet laterally and in line-space direction, and a table for said last-mentioned gages directed rearwardly towards the lower part of the platen. 70
- 40 4. The combination, in a fan-fold typewriting machine, of a table, and a gage thereon for collating a loose sheet with the forms of a web, said table and gage spaced forwardly from the platen, said gage slidably mounted upon said table, the latter being fast to the front bar of the carriage, said table being effective to direct the sheet back and down to the platen. 75
- 50 5. The combination, in a fan-fold typewriting machine, of a platen, a table at the delivery side of the platen, a gage, slidably mounted on said table, for positioning a web in a line-space direction, and a gage slidably mounted in a plane tangent to the periphery of the platen, said last-mentioned gage being effective to position a cut form in preliminary registration with the web. 80
- 60 6. The combination, in a web-manifolding typewriting machine, of a revoluble platen, feed-rolls therefor, means at the introductory side of the platen for conducting a work-web thereto, means for elevating the platen away from the feed-rolls preparatory to stripping the carbons, and co-operative leading end collating gages, one 85
- 15 at the delivery side of the platen for positioning the leading end of the web, and the other serving to locate a separate sheet in register with the leading end of the web, and mounted forwardly from the platen to permit the downward insertion of the separate work-sheet bottom edge foremost between the platen and the feed-rolls from the front, so that the leading ends of the work-sheet and web will register when the platen is then lowered to normal position. 90
- 25 7. The combination in a web-manifolding typewriting machine, of a revoluble platen, feed-rolls therefor, means at the introductory side of the platen for conducting a work-web thereto, means for elevating the platen away from the feed-rolls preparatory to stripping the carbons, co-operative leading end collating gages, one at the delivery side of the platen for positioning the leading end of the web, and the other serving to locate a separate sheet in register with the leading end of the web, and mounted forwardly from the platen to permit the downward insertion of the separate work-sheet bottom edge foremost between the platen and the feed-rolls from the front, so that the leading ends of the work-sheet and web will register when the platen is then lowered to normal position, and a clip on the last-mentioned gage to yieldingly hold the separate sheet in fixed position while the web is being manipulated and the platen is being lowered. 95
- 30 8. The combination in a web-manifolding typewriting machine, of a platen, feed-rolls therefor, means at the introductory side of the platen for conducting a work-web thereto, means for elevating the platen away from the feed-rolls preparatory to stripping the carbons, an adjustable collating gage at the delivery side of the platen for positioning the leading end of the web, and adjustable means mounted at a distance forwardly from the front of the platen cooperating with said gage to collate a separately and downwardly introduced sheet in register with the leading end of the web and permitting the bottom edge of the separate sheet to be inserted foremost between the platen and the feed-rolls from the front, so that the leading ends of the separate sheet and web will register when the platen is then lowered to normal position. 100
- 35 9. In a typewriting machine, in combination, a revoluble platen, feed-rolls therefor, and sheet-collating devices including means at the introductory side of the platen for conducting thereto a record-sheet having a superposed carbon, means for elevating the platen away from the feed-rolls, and co-operative leading end collating gages, one at the delivery side of the platen for positioning the leading end of the record-sheet, 105
- 40 110
- 45 115
- 50 120
- 55 125

- and the other serving to locate a separate work-sheet in register with the leading end of the record-sheet and mounted forwardly from the platen in position to direct 5 downwardly and rearwardly the separate work-sheet bottom edge foremost between the platen and the feed-rolls from the front, so that the leading ends of the work-sheet and record-sheet are brought into register.
10. In a typewriting machine, in combination, a revolute platen, feed-rolls therefor, and sheet-collating devices including means at the introductory side of the platen for conducting thereto a record-sheet having a 15 superposed carbon, means for effecting separation of the platen and feed-rolls, and cooperative leading end collating gages, one at the delivery side of the platen for positioning the leading end of the record-sheet 20 and the other serving to collate a separate work-sheet in register with the leading end of the record-sheet and mounted forwardly of the platen upon a table which is positioned to direct downwardly and rearwardly 25 the separate work-sheet bottom edge foremost between the platen and the feed-rolls, so that the leading ends of the work-sheet

and record-sheet are brought into register upon rearward feeding of the sheets.

11. In a typewriting machine, in combination, a revolute platen, feed-rolls therefor, sheet-collating devices including means at the introductory side of the platen for conducting thereto a record-sheet having a superposed carbon, means for effecting separation of the platen and feed-rolls, and cooperative leading end collating gages, one at the delivery side of the platen for positioning the leading end of the record-sheet and the other serving to collate a separate work-sheet in register with the leading end of the record-sheet and mounted forwardly of the platen upon a table which is positioned to direct downwardly and rearwardly 30 the separate work-sheet bottom edge foremost between the platen and the feed-rolls, so that the leading ends of the work-sheet and record-sheet are brought into register upon rearward feeding of the sheets, a knife located above the platen, and a cutting-off 35 gage for positioning the record-sheet preparatory to severing a typed portion thereof. 40 45 50
